(57) CLAIM

The ornamental design for a table, as shown.

DESCRIPTION

FIG. 1 is a side perspective view of a table showing a new design, with a central block on the upper surface equipped with electrical sockets and for receiving desk top accessories; and,

FIG. 2 is a front perspective view thereof.

1 Claim, 1 Drawing Sheet

FIG. 1

FIG. 2

UNITED STATES PATENT AND TRADEMARK OFFICE
CERTIFICATE OF CORRECTION

PATENT NO. : Des. 504,253 S
DATED : April 26, 2005
INVENTOR(S) : Bouroullec et al.

It is certified that error appears in the above-identified patent and that said Letters Patent is hereby corrected as shown below:

Drawing sheet, consisting of Fig. 1 and Fig. 2, should be deleted and replaced with the attached drawing sheet, consisting of Fig. 1 and Fig. 2.

Signed and Sealed this

Fourteenth Day of March, 2006

A handwritten signature in black ink, appearing to read "Jon W. Dudas". The signature is written in a cursive style with a large, stylized "J" at the beginning.

JON W. DUDAS
Director of the United States Patent and Trademark Office
